US0D1061608S

(12) United States Design Patent (10) Patent No.: US D1,061,608 S
(45) Date of Patent: * Feb. 11, 2025

(54) DISPLAY SCREEN OR PORTION THEREOF WITH ICON

(71) Applicant: Apple Inc., Cupertino, CA (US)

(72) Inventors: Kevin Will Chen, Cupertino, CA (US);
Alan C. Dye, San Francisco, CA (US);
Jonathan P. Ive, San Francisco, CA (US); Christopher Wilson, San Francisco, CA (US)

(73) Assignee: Apple Inc., Cupertino, CA (US)

() Term: 15 Years

(21) Appl. No.: 29/824,707

(22) Filed: Jan. 26, 2022

Related U.S. Application Data

(63) Continuation of application No. 29/756,983, filed on Nov. 2, 2020, now Pat. No. Des. 942,474, which is a continuation of application No. 29/733,390, filed on May 1, 2020, now Pat. No. Des. 902,250, which is a continuation of application No. 29/704,999, filed on Sep. 9, 2019, now Pat. No. Des. 883,307, which is a continuation of application No. 29/627,105, filed on Nov. 22, 2017, now Pat. No. Des. 859,463, which is a continuation of application No. 29/602,870, filed on May 4, 2017, now Pat. No. Des. 803,879, which is a continuation of application No. 29/565,411, filed on May 20, 2016, now abandoned, which is a continuation of application No. 29/534,857, filed on Jul. 31, 2015, now Pat. No. Des. 757,084, which is a continuation of application No. 29/501,230, filed on Sep. 2, 2014, now Pat. No. Des. 735,754.
